SOLOMON OPPENHEIMER, OF PERU, INDIANA.

Letters Patent No. 61,090, dated January 8, 1867.

IMPROVEMENT IN CONSTRUCTING LATCH-BOLTS.

The Schedule referred to in these Letters Patent and making part of the same.

TO ALL WHOM IT MAY CONCERN:

Be it known that I, SOLOMON OPPENHEIMER, of the town of Peru, Miami county, Indiana, have invented a new and improved Mode of Constructing the Latch-Bolts in Door-Locks, and in a manner so as the lock can be used and applied to either a right or left door; and I hereby declare that the following is a true, full, and exact description of the same, reference being had to the accompanying drawings, and the letters of reference marked thereon.

I construct my reversible latch-bolt in two separate parts, one part consisting of the forks on which the tumblers works, and the other part is the shank with the bolt-head to it.

Figures 2, 3, and 4, show different kinds of shanks having my improvement, which consists in affixing flanges to their sides, as seen at *a' a'* on those figures, and also small projections on beads, *b b*, the use and application of which will be explained hereafter.

To the forked part of the latch-bolt, fig. 1, is fitted a pair of additional prongs, *A A*, which are far enough apart from each other so as to admit the width of the shank between them. Upon the forward ends of these prongs are placed upright flanges, *c c*, which form a kind of clamps to hold the shank, when placed between them, firm and steady, and prevent it from side-play. By means of these raised flanges being before, and the connecting-ridge *B*, (fig. 1,) being behind, a recess is formed as seen at *d d*, suitable for the shank to fit into; this is for to hold the parts together when in use. But the ridge *B*, (fig. 1,) is not necessary for either pushing or drawing the shank when the lock is in action, because there are other and additional means provided, namely, those beads or projections on the sides of the shanks marked with letters *b b*, on figs. 2 and 4, and which fit into corresponding grooves on the inside of the clamps, as seen in fig. 1. The round nose *D*, on fig. 3, and the grooved one *E*, fig. 2, are two different kinds of guides running in suitable grooves and ridges in the lock-plates. It will be seen by the description given and by examining the drawings, that when the latch-bolt is to be reversed from a right to a left, or from left to a right-handed lock, it is only necessary to lift the shank out of the clamps and return it again with any side turned up, and this can be done without trouble or interference with the other parts of the locks, for there is no screw, pin, or slide to be drawn as in some other kind of locks.

I do not make any claim as to constructing a door-lock where the latch-bolt is made in two or more parts, for I know that is nothing new, being done on many locks in use.

But what I claim as my invention, and for which I desire to secure Letters Patent, is—

The peculiar manner and means by which the two several parts are connected and held together, namely: The additional prongs *A A* and the raised flanges *c c* on the same, forming clamps for holding the shank firm and steady.

I also claim affixing side-flanges *a' a'*, and beads or projections *b b*, to the shank for the purpose as stated; also the grooves in the clamps for the said beads or projections to fit into.

SOLOMON OPPENHEIMER.
